Primary Examiner — Rhea Shields

(74) Attorney, Agent, or Firm — David B. Gornish;
Eckert Seamans Cherin & Mellott LLC(57) **CLAIM**

The ornamental design for a container for storage, as shown and described.

DESCRIPTION

FIG. 1 is an isometric view of a container for storage showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The features shown in broken lines in the drawings depict unclaimed subject matter only and form no part of the claimed design.

1 Claim, 5 Drawing Sheets(56)
